UNITED STATES PATENT OFFICE.

FRED J. BULLOCK, OF SHORTSVILLE, NEW YORK, ASSIGNOR TO PAPEC MACHINE COMPANY, OF SHORTSVILLE, NEW YORK, A CORPORATION OF NEW YORK.

ENSILAGE-CUTTING-WHEEL CONSTRUCTION.

1,265,604.

Specification of Letters Patent.

Patented May 7, 1918.

Application filed May 2, 1916. Serial No. 94,941.

To all whom it may concern:

Be it known that I, FRED J. BULLOCK, a citizen of the United States, residing at Shortsville, in the county of Ontario and State of New York, have invented certain new and useful Improvements in Ensilage-Cutting-Wheel Construction, of which the following is a specification, reference being had therein to the accompanying drawing.

10 This invention relates to certain new and useful improvements in ensilage cutting wheel construction and more particularly to the construction of the fan blades used in connection with ensilage cutters, the object 15 being to provide a cutting wheel construction having means for holding the fan blade supports in such a manner that the strain on the connecting rivets is reduced.

Another object of my invention is to provide a fan construction in which the blade is formed of two sections, one section being adjustably mounted in respect to the other section so that the same can be adjusted as the blade wears.

25 Other and further objects and advantages of the invention will be hereinafter set forth and the novel features thereof defined by the appended claims.

In the drawing—

30 Figure 1, is a detail section through the cutting wheel casing, showing the cutting wheel in section and one of the fans in elevation;

Fig. 2, is a detail plan view showing the 35 position of the fan on the cutting wheel;

Fig. 3, is a detail side elevation of the cutting wheel showing the fan in side elevation; and

Fig. 4, is a detail view of the fan partly 40 in section, showing the manner of mounting the detachable blade section.

Fig. 5 is a detail section through the cutting wheel showing a slightly modified form of fan construction.

45 Like numerals of reference refer to like parts in the several figures of the drawings.

In the drawing, 2 indicates the cutting wheel casing, 1 the cutting wheel which is provided upon opposite faces with lugs 3 and 4 adapted to engage the legs 5 of a fan support 6 which is provided with an integral blade portion 7 and a removable blade portion 8.

50 The fan support 6 is adapted to straddle the cutting wheel 1, the legs extending be-

tween the lugs 3 and 4 and are secured by transversely arranged rivets 9.

It will be seen that the lugs 3 and 4 are so placed on the cutting wheel, that when the legs are in the position as shown in Fig. 3, 60 the rivets will be relieved of the strain so as to prevent the rivets from shearing off when the cutting wheel is in operation.

The support 6 is provided with oppositely disposed apertured arms 10 adapted to 65 register with apertured lugs 11 formed on the movable section 8 of the fan blade and between which is adapted to be arranged a filler 12 for holding the arms 10 and lugs 11 the proper distance apart, so as to adjust 70 the movable section in respect to the rigid section 7 whereby the edge of the movable section can be adjusted within the fan casing at the proper distance from the inner wall thereof and as the blade wears the filler 12 75 can be removed and a thinner filler substituted therefor.

The movable section is secured to the support by bolts 13 passing through the apertured lugs 11, filler 12 and arms 10 the nuts 80 thereof, being preferably secured by cotter pins as shown.

In the construction of fan as shown in Fig. 5, the cutting wheel 1' is provided with lugs 3' and 4' upon one side thereof between 85 which is adapted to be arranged a fan support 5' which is provided with an integral blade portion 7' and a removable blade portion 8'.

The support 5' is secured in position on 90 the cutting wheel 1' on rivets 9' and is provided with an apertured arm 10' adapted to register with an apertured lug 11' formed on the movable blade section 8' of the fan blade and between which is adapted to be 95 arranged a filler 12' for holding the arm 10' and 11' the proper distance apart so as to adjust the movable section in respect to the rigid section. A bolt 13' is employed for securing the movable section to the support. 100

In this construction it will be seen that I have provided a cutting wheel with a fan support and blade which is adapted to be used in connection with an ensilage cutter in which the cutting wheel is mounted adjacent one wall of the casing.

It will be seen that in the preferred form and in the modification, the fan support is provided with an arm under which a lug of the movable blade section is mounted in such 110

a manner that the outward movement of the movable blade section is limited so that it is impossible to become detached from the support as long as the bolt remains in position 5 even if the nut should become accidentally detached.

From the foregoing description, it will be seen that I have provided an ensilage cutting wheel construction having means for 10 mounting the fan supports thereon in such a manner that they are held rigidly so as to prevent the strain from being placed upon the securing rivets, the supports being formed with a rigid blade section and a movable blade section which can be adjusted in 15 respect to the rigid section.

I claim:

1. A wheel having spaced lugs formed on the sides thereof, supports provided with 20 legs embracing said wheel extending between said lugs, fastening members connecting said legs, said supports being provided with integral fan blades, and adjustable fan blades carried by said supports.
2. A wheel having supports provided with spaced legs secured thereto, said supports having integral fan blade portions and movable fan blade portions, the face of the adjustable blade portion being flush with 30 the integral portion of said supports.
3. A wheel having a fan support provided with spaced legs embracing the wheel and extending outwardly therefrom forming an integral blade portion for said support, said 35 support having an adjustable blade section secured thereto having its face flush with the integral blade portion.
4. A wheel having fan supports secured thereto provided with integral blade portions, and adjustable blade portions carried 40 by said supports, the adjustable blade portion having a face flush with the integral blade portion of said support.
5. A wheel having spaced lugs secured to 45 the side faces thereof, a fan support provided with spaced legs straddling said support and extending between the lugs thereof, said support being provided with an integral blade portion, and an adjustable blade 50 portion carried by said support.
6. A wheel having a fan support secured thereto provided with integral blade portions, said support being provided with oppositely disposed apertured arms, a blade 55 section having apertured lugs registering

with the apertures of said arms, bolts passing through said apertured lugs and arms, for securing said blade section to said support.

7. A wheel for ensilage cutters having 60 supports secured thereto and extending outwardly beyond the periphery thereof provided with integral blade portions, said supports having apertured arms, a blade section having apertured ears mounted on said support in alinement with the apertured arms, a filler mounted upon said apertured arms, and bolts passing through the apertured ears and arms, for securing said blade section to said supports. 70

8. A wheel having a support mounted thereon provided with an apertured arm, a movable blade portion mounted on said support provided with an apertured lug arranged under said arm and a bolt passing 75 through said arm and lug for securing said blade to said support.

9. A wheel having a support secured thereto, provided with an integral fan blade portion, said support being provided with 80 an apertured arm, a movable fan blade section mounted upon said support having an apertured lug arranged under said apertured arm, and a bolt passing through said apertured arm and lug for securing said 85 movable blade section to said support.

10. A wheel having a support secured thereto provided with an integral fan blade portion, and a movable blade section adjustably mounted upon said support, said 90 support having arms and the movable blade section lugs arranged under said arms.

11. A wheel having a support secured thereto provided with an integral blade portion extending outwardly beyond said 95 wheel, a movable blade section carried by said support, said support being provided with an apertured arm, an apertured lug extending from said movable blade section under said apertured arm, a filler arranged 100 between said apertured arm and apertured lug, and a bolt passing through said apertured arm and lug for securing said movable blade section to said support.

In testimony whereof I hereunto affix my 105 signature in the presence of two witnesses.

FRED J. BULLOCK.
